US0D1057985S

(12) **United States Design Patent** (10) **Patent No.:** **US D1,057,985 S**
(45) **Date of Patent:** **** Jan. 14, 2025**

(54) **MASSAGER**

(71) Applicant: **Dongguan Mimao Electronic Technology Co., Ltd.**, Dongguan (CN)

(72) Inventor: **Qinling Wang**, Heyuan (CN)

(**) Term: **15 Years**

(21) Appl. No.: **29/929,152**

(22) Filed: **Feb. 20, 2024**

(30) **Foreign Application Priority Data**

Sep. 7, 2023 (CN) 202330579319.4

(51) **LOC (15) Cl.** **24-01**

(52) **U.S. Cl.**

USPC **D24/215**

(57) **CLAIM**

The ornamental design for a massager, as shown and described.

DESCRIPTION

FIG. 1 is a perspective view of a massager showing my new design;

FIG. 2 is another front perspective view thereof;

FIG. 3 is a rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines in the drawings illustrate portions of the massager that form no part of the claimed design.

1 Claim, 9 Drawing Sheets
